UNITED STATES PATENT OFFICE.

EMIL PREIN, OF HANOVER, GERMANY, ASSIGNOR TO PREIN-GEWEBE ACTIEN-
GESELLSCHAFT, OF HANOVER-LINDEN, GERMANY, A FIRM.

APPARATUS FOR CLEANING YARN.

1,144,864.

Specification of Letters Patent. Patented June 29, 1915.

Application filed September 24, 1913. Serial No. 791,539.

To all whom it may concern:

Be it known that I, EMIL PREIN, subject of the King of Prussia, German Emperor, and resident at Hanover, in the Province of 5 Hanover, Kingdom of Prussia, German Empire, have invented certain new and useful Apparatus for Cleaning Yarn, of which the following is a specification.

As is well known, weaving yarns especially those of flax, hemp or jute as also cotton are liable to have attached, numerous strawy and other vegetable fragments which injure the fabric and should consequently be removed before the yarn is woven. 10 In this process of removal, however, it is very desirable that the small filaments adherent to the yarn shall not be removed along with straws or other foreign bodies because these little filaments are desirable to 15 be woven into the fabric inasmuch as they add to its quality.

The object of the present invention consists in a new and practical arrangement for the cleaning of yarns. In accordance therewith, a series of rough bodies are freely suspended between which the threads are guided in close contact. It is moreover advantageous to support the cleaning bodies in a liquid through which the filaments pass. 20 The cleaning bodies themselves are preferably formed of wood or other light material in order to make them as light as possible, which material is covered with some hard substance such as Naxos emery or the like. 25 By an arrangement of this kind, the threads are easily separated from the adherent strawy filaments and the like without any injury. By the free suspension of the cleaning bodies any breakage of the filaments is 30 prevented, because the suspended bodies can easily move apart. Preferably, the filaments are somewhat shaken or set in motion by suitable mechanism, and consequently impelled frequently against the surrounding 35 cleaning bodies. On the passage of the filaments through the liquid receptacle in which also the cleaning bodies are immersed, a specially favorable action is obtained, inasmuch as the liquid imparts to these bodies 40 a greater inertia, so that they only move 45 away to a very slight degree on contact.

In order that the light bodies shall not float upward in the liquid, they are weighted to the requisite degree.

In the accompanying drawing is illustrated diagrammatically a construction of the invention.

The filament *a* passes over the rollers *b*, *c* *d* through the liquid receptacle *e*. Close around the parts of the filament which dip 55 into the liquid there are freely suspended on strings the cleaning bodies *f* and brought as near as possible without entire contact to the filaments.

The filament is preferably guided vertically into the receptacle because in this manner the cleaning bodies can be suspended at various heights close around the filaments. Obviously, there are also other arrangements possible. In order to shake the filament about, it can on entrance into the liquid, and if needful also at other points during its passage be seized by suitable little levers provided with loops and caused to oscillate. For the same purpose also the 70 rollers might be caused to move about, over which the filament passes.

Having now particularly described and ascertained the nature of my said invention and in what manner the same is to be performed, I declare that what I claim is:—

1. Apparatus for treating yarn comprising a tank, rolls for supporting and guiding the yarn in transit through the tank, and floating bodies in the line of travel of the 85 yarn and on opposite sides thereof.
2. In apparatus for treating yarn having a liquid holding tank and rolls for supporting and guiding the yarn through the liquid in the tank, bodies having roughened surfaces freely suspended in the liquid and in the line of travel of the yarn, to remove by friction the extraneous fibers from the yarn.

In testimony, whereof I have signed my name to, this specification in the presence 95 of two subscribing witnesses.

EMIL PREIN.
